KEITH O. GUTHRIE, OF NEW YORK, N. Y., ASSIGNOR TO MABEL S. GUTHRIE, OF BROOKLYN,
NEW YORK.

MOLD-PANEL.

No. 906,493.

Specification of Letters Patent.

Patented Dec. 8, 1908.

Application filed August 15, 1907. Serial No. 388,686.

To all whom it may concern:

Be it known that I, KEITH O. GUTHRIE, a citizen of the United States, residing at Brooklyn, in the city of New York, county 5 of Kings, and State of New York, have invented certain new and useful Improvements in Mold-Panels; and I do hereby declare the following to be a full, clear, and exact description of the invention, such as 10 will enable others skilled in the art to which it appertains to make and use the same.

The object of my invention is to provide an improved panel for the construction of concrete buildings and the like.

15 In the construction of concrete buildings, temporary molds are formed for sections of the walls, floors, etc., and these molds are filled with the concrete which has been properly mixed and tempered. After the 20 concrete has set, the temporary molds are removed and new molds erected for other sections of the building. I aim to improve upon the construction of such buildings, as heretofore practiced, by supplying improved 25 mold panels of a type which will be hereafter fully described, and which are capable of being used in an improved way, which facilitates the erection and knocking down of the temporary mold, which are light and 30 easily handled, which are capable of forming a smooth surface, and which may be used repeatedly in the construction of the temporary molds.

35 The nature of my improvements will be understood from a consideration of the following description in connection with the accompanying drawings, in which the same letters of reference refer to like parts throughout.

40 In the drawings, Figure 1 is a plan view of a concrete wall in the construction of which my improvements are used; Fig. 2 is a perspective view of one of my improved panels, with parts broken away; Fig. 3 is a detail 45 view of an approved means for attaching the outer faces of the panels to the interior supporting parts; Fig. 4 is a detail, sectional elevation showing the manner of supporting the panels in place in the mold; Fig. 5 is a 50 longitudinal section of a modified form of panel, and Fig. 6 is a plan view of the same with the upper sheet removed; Fig. 7 is an elevation of the outer corner of a wall mold

in which my improvements are applied; Figs. 8 and 9 are sections of irregular forms 55 constructed in accordance with my invention; and Fig. 10 is an elevation of Fig. 9.

The concrete wall 1 is constructed by filling in the temporary mold made from a series of mold panels 2 of an improved construction, 60 which I will now describe. Each panel is composed of two outer thin metallic sheets 3 separated and rigidly supported by the truss web or tie member 4; which may be made of a continuous metallic sheet or separate 65 sheets, as circumstances may dictate. As indicated in Fig. 1, this truss web or tie member is riveted along a flat portion 5 to one of the plates 3. It is then extended diagonally across the space between the 70 plates 3 and is riveted along a flat portion 6 to the other plate. It then extends diagonally again to the first plate and is riveted along a second flat portion 5 and so on throughout the extent of the panel. The 75 panel is further strengthened and closed at its edges against the admission of dirt by channel beams 7 riveted to the plates 3. The rivets securing the outer plates 3 to the supporting structure should be counter-sunk 80 to a flat surface, against which the concrete may be filled, and though it is advisable to counter-sink the rivets on both sides of the panel in order that either side may be used interchangeably, it is possible to use panels 85 in which the rivets are counter-sunk on but the one side, which is used to form the inner face of the mold.

For the purpose of affording a secure fastening at the rivet, and at the same time to 90 counter-sink the rivet in the manner desired, I prefer to adopt the construction which is illustrated in detail at Fig. 3. In this construction a hole is punched through the plate 3 and the underlying flat portion 6 or other 95 like part, and the sides of this hole are drawn down into a cup-shape by appropriate dies, thus bending down the flat surface of the plate 3 and the flat surface of the part 6 about the hole as illustrated in Fig. 3. A suitable 100 rivet 9 is then passed through the hole and upset about the edges of the cup, as shown. This arrangement affords a secure lock in which the walls of the cup formed from the 105 surfaces of the plate 3 and the part 6 are positioned to resist all shearing strains, and

it is rendered practically impossible to tear out the sheets 3 or 6 from about the head or the upset portion of the rivet.

It will be observed that in the construction 5 of the panel above described, the channel beams 7 close and stiffen the outer edges of the panel and act as plate girders against pressure of the concrete. The truss web 4 acts as a tie member in the direction of the 10 truss and as a series of plate girders along the length of the web. The flat plates forming the faces of the panels constitute continuous chords for the truss and flanges for the girders. By this construction, I am able to produce 15 a light, metallic panel which is extremely durable and so rigid that it will resist the pressure of the cement when supported only at its corners, as illustrated in Figs. 1 and 7.

20 In Figs. 5 and 6, I have shown a modified form of panel in which the outer edges are closed by channel beams as before, but there is substituted on the inside, for the truss web 4, two series of flat truss-bars 10 and 11 running 25 at right angles to one another and riveted to the plates 3, as before. With these improved panels, I erect the temporary molds in the manner which is illustrated in Figs. 1 and 7. For the purpose of erecting a mold 30 in accordance with this feature of my invention, a series of studs 12 are set up about the place at which the wall or other structure is to be built, and positioned a considerable distance from the wall. At each corner of 35 each panel is secured an eye-bolt 15 to which is attached a strap 16 having an eye at its outer end. The panels are fastened in proximity to, but spaced away from, the studs by driving pins 17 through the eyes at the outer 40 end of the straps 16 into the studs, and when so attached to the studs, the panels are rigidly secured in position to form a flat surface for the wall by driving the wedges or blocks 18 between the panels and the studs. 45 By means of these straps secured to the panels, the individual panels, having been accurately positioned by the use of a spirit level, or the like, may be rapidly and easily fixed in position by laying the straps against the 50 adjacent studs and driving a pin through each strap into the stud. The panels may then be blocked up by a single set of blocks, thus avoiding the difficulties of adjustment and other disadvantages attendant upon the 55 use of yokes or stirrups attached to the panels and slipped over the studs or other known ways of adjusting and holding the panels in position.

60 The mold being erected in the manner above described, affords a smooth, flat, metallic surface for both sides of the inclosed wall, and after the cement, or like material, has been filled in and has set to form the wall, the panels may be rapidly and conveniently 65 removed by knocking down the wedges 18

and withdrawing the pins 17, without in any way disturbing the studs. A similar mold may then be erected from the same panels, and if the second mold is a vertical continuation of the wall already formed, with the 70 same studs.

My improvements lend themselves readily to the erection of walls with curved or other irregular surfaces and to the formation of cornices and the like.

75 In Figs. 8, 9 and 10, I have illustrated panels made in irregular shapes and in accordance with my invention. In Fig. 8 is shown in section a panel having a reversed curvature, and in Figs. 9 and 10 is shown a 80 panel having a simple curve. In the construction of such irregular forms I support the sheet of metal forming the face which is placed next to the concrete, by a tie member like those described above, and having bent 85 the plate to the desired shape, I attach a second properly bent plate to the flat portions of the tie member to form a continuous flange for the truss-structure as in the manner which has been described in connection with Fig. 2. 90

It will be observed, however, that the bent form of these irregular shapes gives them a power of resistance to the pressure of the concrete, and it is, therefore, not necessary to support them by truss-structure of so great 95 strength as in the case of flat panels. Furthermore it is unlikely that such irregular forms will be available for use in any great number of buildings. That is, they are likely to be of a more temporary nature de- 100

signed to fulfil the requirements of a particular structure and unavailable for use in other structures. So also it is seldom necessary that both sides of the walls should have the curvature, the irregular forms being com- 105 monly applied but to one side of the wall. The result of these conditions is that it is often advantageous to make these irregular forms of a more temporary and less durable construction and to construct them with but 110

one continuous surface thus saving in first cost. In Fig. 10 I have indicated one construction which may be adopted. It will be observed that in this figure the truss-web 4 described in connection with Fig. 2 and hav- 115 ing the portions 6 riveted to the sheet, is used, but in place of the continuous sheet forming the other side of the panel are substituted a series of bent strips 27, which are riveted or bolted to the portions 5 and serve as flanges 120 for the truss structure. So also in this arrangement the channel beams along the curved edge of the panel are dispensed with.

This cheapening and simplification of the irregular panels may be carried still further by 125 reducing the length of the truss-webs, or by substituting one or more flat truss-bars like the truss-bars 10 illustrated in Figs. 5 and 6. Owing, however, to the strength acquired by the curvature of these irregular panels, it is 130

seldom necessary to use truss-bars running in that direction in which the lines of the panel are straight, so that the supporting truss-structure may resolve itself into one or more 5 truss-bars like 10, or their equivalent, running along the line of curvature, and braced by bent metallic strips such as the strips 27 shown in Fig. 12, or their equivalent. It will be appreciated by those skilled in the art that 10 a like simplification and cheapening of parts may be adopted with flat panels where for any reason they are to be made of a relatively temporary nature, the complete construction of flat panels illustrated and described above 15 lending itself peculiarly, however, to the construction of panels of uniform size and great durability which may be repeatedly used in building different structures.

It will be observed that it is characteristic 20 of my improved panels that by virtue of the truss construction they may be made of the desired strength and rigidity from three elements—two chords and a web—each of which is in itself flexible, so that when the 25 flexible web has been attached to one of the flexible chords—as the face plate—the truss structure is completed and rendered rigid throughout by attaching the other chord, which may in itself be flexible and therefore 30 capable of being bent to the required shape without any difficulty.

Though I have illustrated the channel beams 7 at the end of the panel separate 35 from the truss-web 4 they may, if desired, be made continuous with the truss-web, which will be properly bent for that purpose, as shown in Fig. 1 at a. My improved panels also lend themselves readily to the construction of ornamented surfaces. To make any 40 desired break in the planesurface, to resemble joints in stone work, or to form any kind of ornamentation, blocks or strips of wood or of sheet metal properly bent or stamped may be temporarily attached to the face of the panel 45 by means of light bolts running through the panels, or the like, and this may be done without injuring the strength of the panel or destroying its surface to such an extent as to make it unavailable for a later use.

50 What I claim is:—

1. An improved mold panel for concrete construction comprising a thin flexible metallic face-plate, a flexible metallic web-section supporting and reinforcing the face-plate, and a stiffening chord attached to the web-section to form the whole into a continuous rigid truss structure.

2. An improved mold panel for concrete construction comprising a thin flexible metallic face-plate supported and reinforced by a web-section comprising plate-girders extending in one direction of the panel and having their inner flanges secured to the face-plate, in combination with a chord extending

across the girders and secured to the outer 65 flanges thereof to form the whole into a continuous rigid truss structure.

3. A flexible material for constructing mold panels for concrete construction comprising a thin flexible metallic face-plate, a 70 flexible metallic truss web-section of thin metal bent to form diagonally extending reaches and intermediate connecting portions, alternate intermediate portions being secured to the face-plate and the remaining 75 alternate intermediate portions adapted to be secured to a stiffening chord to form the whole into a continuous rigid truss structure.

4. An improved mold panel for concrete construction comprising a thin metallic face-plate supported and reinforced by sheet metal extending across the face-plate and bent to form a series of connected truss webs 80 extending along the face-plate, and a chord secured to all of the individual webs along 85 the panel to form the whole into a continuous rigid truss structure.

5. An improved panel for the purpose described comprising two thin metal plates, separated and reinforced by sheet metal 90 interposed between the plates and bent to form a truss-web, the web being attached to the plates to form the whole into a continuous rigid truss structure, and channel beams secured between the edges of the plates to 95 close the edges of the panel.

6. An improved panel for the purpose described comprising two thin metal plates, separated and reinforced by a sheet metal truss-web 4 having the flat portions 5 and 6 100 attached to said plates, and channel beams attached to the edges of said plates to close the edges of the panel; substantially as described.

7. An irregular panel of the character described, comprising a curved thin metallic face plate supported and reinforced by sheet metal extending in the direction of the straight lines of the panel, and bent to form a truss-web extending along the line of curvature, and a bent chord extending along the line of curvature, the face plate, web, and chord being attached to one another to form the whole into a continuous rigid truss structure.

8. An irregular panel of the character described comprising a thin flexible curved metallic face plate supported and reinforced by a flexible metallic truss-web having a continuous chord extending along the line of 120 curvature.

In testimony whereof I affix my signature, in presence of two witnesses.

KEITH O. GUTHRIE.
